UNITED STATES PATENT OFFICE.

ROBERT R. THOMPSON, OF LOS ANGELES, CALIFORNIA; MARY W. THOMPSON
EXECUTRIX OF SAID ROBERT R. THOMPSON, DECEASED.

OSCILLATING SIGNAL.

Application filed November 22, 1919. Serial No. 339,788.

This invention relates to signals of the general class used as railway signals; although it will be apparent that the invention is not at all limited to being used as a railway signal.

There are many objects, and corresponding accomplishments, of the invention too numerous to mention briefly without first giving a more or less complete understanding of the mechanism in detail. I shall therefore leave these objects and features to be understood from the following detailed description of a preferred form of the invention; it being understood, however, that these details are not necessarily a limitation on the invention and that I give such fully detailed description for the purpose of giving a clear understanding of my invention through one specific form of it, and not for the purpose of limiting the invention in its broader aspects. Accordingly I have illustrated such specific form of mechanism in the accompanying drawings, in which—

Fig. 1 is a plan of the mechanism; Fig. 2 is a side elevation of the same; Fig. 3 is a vertical longitudinal section taken as indicated by lines 3—3 on Figs. 1 and 8; Fig. 4 is a detail section taken as indicated by line 4—4 on Figs. 2 and 3; Fig. 5 is a detail section taken as indicated by line 5—5 on Fig. 2; Fig. 6 is a diagram showing the electrical connection of the complete signal; Fig. 7 is an end elevation of the mechanism; Fig. 8 is a transverse section taken as indicated by line 8—8 on Fig. 3; Fig. 9 is a front elevation of the complete signal, showing the signal member or arrow and indicating its movement; and Fig. 10 is a side elevation of the complete signal with its enclosing case, these last two mentioned figures being greatly reduced.

In the drawings the numeral 10 designates a suitable base plate upon which the whole mechanism may be mounted. Upon this base plate I erect a pair of upright plates 11 and 12, which carry the major part of the motor mechanism and switches. The hollow main shaft 13 of the motor mechanism is carried in anti-friction bearings 14 in plates 11 and 12. The signal arrow or other visual indicator A (the details of which need not be entered into here) is mounted upon the forward end of shaft 13, through the medium of the mounting flange

16. The armature and field and commutator of the motor mechanism are mounted between the two plates 11 and 12; and the shaft 13 extends behind the plate 12 and there carries the controlling switch mechanism 17. The reversing switch 18, which is controlled in action by the controlling switch mechanism 17, is mounted upon the rear end of base 10.

A non-magnetic bushing 20 is rigidly mounted on shaft 13 and carries a circular iron plate 21 upon which the several armature cores 22 are rigidly mounted and carried. These armature cores 22 extend axially from plate 21 and are provided with windings 23. These windings 23 are connected together and connected to conductor bars 24 which lead to commutator bars 25; the windings and connections being in the ordinary and well known manner for a four pole motor. Conductor bars 24 and commutator bars 25 are preferably integral; the commutator being formed by the bars 25, supported at their inner ends by bars 24 which are screwed or otherwise set on the insulating plate or disk 26, and supported at their outer ends on a disk 27. A very simple and inexpensive commutator is thus made.

At their ends, the armature cores 22 carry a magnetic armature ring 30, secured to the armature cores so as to be rigidly carried by the armature cores and so as to properly space the armature cores apart at their ends. This armature ring 30 is carried in proximity to the four field poles 31 which are rigidly mounted upon the plate 11. These field poles are segmental in shape as shown in Fig. 8, and to them are secured the field cores 32. These field cores extend also axially of the machine and at their other ends carry four smaller pole pieces 33 which stand close to the magnetic armature plate 21. The magnetic gap between pole pieces 33 and plate 21 is as small as practicable; and the magnetic gap between pole pieces 31 and armature ring 30 is also as small as is practicable in a machine of this character. Armature ring 30 may have a flange or lip 34 overhanging the pole pieces to reduce magnetic leakage. Armature ring 30 and plate 21 are of iron of high reluctance; and ring 30 is of small cross-section. This is to prevent the magnetism generated by the armature magnet coils from having a mag-

100
105
110

netic "short circuit" through the armature structure itself; the high reluctance makes a condition that causes the magnetic lines of force to pass to and through the pole pieces 31 and 33 rather than through parts 30 and 21. There are four sets of magnetic field poles 31, 33. Each set is equipped with two cores 32 (in parallel) with suitable windings 35 which are so connected (for each 10 pole) that the magnetism produced is either south or north, as the case may be. The reason for this construction is to reduce radial dimension of the motor. The pole pieces themselves are alternately of north 15 and south polarity.

Preferably only two sets of brushes 40 are used on the commutator 25, the armature windings being cross connected in the usual and well known manner. Enough has now 20 been described to show, without the necessity of further detailed explanation, how the mechanism just described may act as a rotating motor. It will be seen that the armature, the revolving part, is relatively large; 25 being so not only on account of the design in general, but also on account of its being outside the field rather than inside. The armature being thus relatively large, its several parts which are located at a comparatively great distance from the center of rotation lend largely to the inertia of the machine, and facilitate its steadiness and smoothness of action. This smoothness of 30 action is also facilitated by the fact that the field has eight poles and that the armature has a large number of coils, all active at all times. And, in spite of the large number of 35 coils, the armature is easily repaired. Being at the outside of the machine, the armature 40 coils may be easily removed; and one or even several of them may be removed, for repairs, etc. without seriously impairing the action of the machine; the voltage on the machine being adjusted to suit the lesser number of armature coils. The field coils are relatively 45 heavily wound so that there is little liability of their being damaged.

Mounted on the rear end of shaft 13 there 50 is a bushing 45 which carries an insulating block 46. Through the upper end of this insulating block there extends a transverse pivot rod 47 and a swinging U-shaped switch arm 48 is pivoted on pivot rod 47 at the upper ends of its arms. The lower end of this 55 swinging U-shaped switch arm carries a contact 49. In order to press contact 49 toward the left in Fig. 3 and thus keep it pressed into good contact with stationary adjustable contacts 50, a suitable spring arrangement is 60 used, in the form shown in detail in Fig. 4. A transverse bar 51 extends across the face of insulating block 46 (see Fig. 7) and has its ends extending over the arms of the switch member 48 below the pivot rod 47. 65 Springs 52 carried by screws 53 press

against the transverse bar 51 and tend to press it back against the insulating block and to press the switch arm 48 back to the left in Fig. 3. The whole construction which has here been explained revolves with the 70 shaft 13; and when, in the course of its movement, the contact 49 rides up over either of the stationary contacts 50, then the contact 49 and the switch arm 48 are pressed slightly outwardly, and the springs 52 keep 75 the contact 49 in good engagement with the stationary contact.

Between upright frame plate 12 and the switch arm mechanism which has just been described, there is mounted a stationary contact carrying plate 60, of insulating material; and upon this plate 60 there is mounted a collector ring 61. A spring metallic contact 62 extends over the top of block 46 and engages collector ring 61. This contact 80 62 is mounted on block 46 by means of a screw or screws 63 which make contact with the pivot rod 47. Thus electrical connection is made to the switch arm 48 and to the contact 49 thereon. On the back side of plate 85 60 there are curved metal plates 66 provided with spaced holes corresponding to the holes 65 in plate 60; and the adjustable contacts 50 are held on the plate 60 in their adjusted position by screws 67 which pass through 90 the contacts 50 and through plate 60 and screw into the metal plates 66.

On insulating plate 60 there are also two other collector rings 70 and 71 which serve to transmit current to the lamp located at 100 L in the signal arrow A. Wires 72 lead to the lamp L through the hollow shaft 13. These wires 72 connect to binding posts 73 mounted in insulating block 46. The ends of these binding posts are provided with 105 spring pressed contact heads 74 which engage the collector rings 70 and 71. The collector rings are appropriately connected into the operating circuit by wires 75 and 76, as will be hereinafter explained.

The reversing switch mechanism at 18 embodies a tilting member 80 pivoted at 81 so as to be easily movable. Member 80 carries at each end four contacts 82^a, 82^b, 82^c, 82^d, and 83^a, 83^b, 83^c, and 83^d; and there are corresponding stationary contacts 84^a, 84^b, 84^c, 84^d, and 85^a, 85^b, 85^c, and 85^d. The movable contacts mounted upon tilting member 80 are connected in pairs; that is, 82^a and 82^b in a pair, 82^c and 82^d in a pair, 83^a and 83^b in a pair, and 83^c and 83^d in a pair; so that 115 the electrical action of these movable contacts is merely to make a connection between the corresponding pairs of stationary contacts. Thus the pair of movable contacts 82^a, 82^b is for the purpose of merely connecting stationary contacts 84^a and 84^b together. Below the tilting member 80 there are two sets of magnets 86 and 87, one set on each 120 side of the pivotal axis of the tilting mem- 125 ber. The magnets 86 and 87 are so arranged 130

ber. These magnets have pole piece 88 adapted to attract an armature 89 secured to the under face of tilting member 80.

Referring now more particularly to Fig. 6, the wiring connections of the device will be explained. The whole mechanism may be operated from any suitable source of current, as from a battery B. A wire 90 will lead from one side of the battery to binding post 91 on the mechanism and a wire 92 will lead from the other side of the battery through a control switch S (which is any kind of a control switch which may be used in the installation of the mechanism as a track signal) to a binding post 93 on the mechanism. From binding post 93 a wire 94 leads to field winding 35. And from the field winding a wire 95 leads to stationary contact 85^a. A branch wire 95^a leads from wire 95 to stationary contact 84^a. From stationary contact 85^b a wire 96 leads to the armature M, a branch wire 96^a connecting into stationary contact 84^c. From the armature a wire 97 leads to stationary contact 85^c, a branch 97^a leading to contact 84^b. From binding post 91 a wire 98 leads to stationary contact 85^d, a wire 99 connecting stationary contact 85^d with stationary contact 84^d. From the battery wire 90 another wire 100 may lead through bell coil 101 (the coil of a signal bell, if it is desired to use a bell in connection with the visual indicator) to the binding post 102 on the machine. From the binding post 102 a wire 103 leads to the left hand contact 50 of the control switch mechanism. From the right hand contact 50 a wire 104 leads to and joins wire 95. From wire 103 a wire 105 leads to the windings of magnets 87. From wire 104 a wire 106 leads to the winding of magnets 86. The windings of magnets 86 and 87 are connected together by a wire 107, and from this wire 107 a wire 108 leads to the swinging switch contact 49 (through the medium of the collector ring 61, contacts 62, and the other parts as previously explained). The end of magnet winding 87 to which wire 105 is connected is also connected to the movable contact 83^c, 83^d. In the diagram this connection is shown by a conductor 109; but in actual practice this connection is made by grounding both the switch contact and this end of the magnet winding. The contact may be grounded by connection 109 extending from it to the metallic strip 109^a at the edge of member 80; the pivot screw 81 grounding the strip 109^a. This arrangement obviates any necessity of making a flexible wire connection to the movable contact. Between wire 98 and wire 105 there is a non-inductive high resistance 110.

Whenever controlling switch S is closed, current will immediately flow from the battery to wire 90, wire 100, bell coil 101, wire 103 and wire 105 to the magnet winding 87

and thence through wire 107 to the other magnet winding 86 and thence through wire 106, wire 104, and wire 95 to the field windings 35 and thence through wires 94 and 92 and switch S back to the battery. Both the magnets 86 and 87 are thus energized and they both act upon the tilting member 80 to draw it downwardly. Now, it is impossible to put the tilting member in such a position that it will not overbalance in one direction or the other; and so it immediately overbalances and the magnets on one side pull it down. It is immaterial which end of the tilting member 80 is pulled down first; but suppose for instance that the left hand end of the member is first pulled down. Movable contacts 83^a, 83^b and 83^c, 83^d, are thus thrown into engagement with the corresponding stationary contacts 85^a, 85^b, 85^c, and 85^d. Immediately this takes place current then flows from the battery through wire 90, wire 98, contact 85^d, contacts 83^a and 83^c, contact 85^c, wire 97, armature windings 23, wire 96, contact 85^b, contacts 83^b, 83^a, contact 85^a, wire 95, field winding 35, wire 94, and wire 92 and switch S to the battery. The motor being thus energized, it commences to rotate; and the connection is such, in this particular case, that the motor commences to rotate, counter clockwise in Figs. 6 and 7. By this rotation switch contact 49 is carried around into engagement with right hand stationary contact 50. The effect of this engagement with contact 50 is simply to short circuit the magnet winding 86; but as the tilting member 80 is already in the position shown in Fig. 6 this short-circuiting of winding 86 has no effect upon the operation of the machine and the motor continues to rotate in the same direction. This rotation then carries contact 49 away from right hand contact 50 and into engagement with the left hand contact 50; and upon that taking place the left hand magnet windings 87 are immediately short circuited, and the right hand magnets 86 (now again energized) then pull the tilting member 80 over to its other position, throwing contacts 82^a, 82^b, and 82^c, 82^d into engagement with the corresponding stationary contacts 84^a, 84^b, and 84^c, 84^d. Current then immediately begins to flow from battery B through wire 90, wire 98, wire 99, contact 84^d, contacts 82^d and 82^c, contact 84^c, wire 96^a, wire 96, armature windings 23, wire 97, wire 97^a, contact 84^b, contacts 82^b and 82^a, contact 84^a, wire 95^a, wire 95, field windings 35, wire 94, wire 92, and switch S, back to the battery. The direction of current through the armature winding having been reversed, there is of course immediately a tendency to stop the counter clockwise rotation of the armature and to start its rotation in the other direction. But the inertia of the rotating system, including the armature and the signal member 130

A, is great enough so that the rotating system is not immediately stopped from rotation, but goes on perhaps for an angle of say 30° or more. During all of this time however, the action of the current is energetically opposing the movement of the rotating system and acting positively to bring it to a stop at a fairly definite point. As soon as the rotating system has stopped rotation in counter-clockwise direction, it immediately starts back in a clockwise direction of rotation. Contact 49 again wipes over the left hand stationary contact 50, but this of course has no effect upon the operation as the tilting member 80 is then being held by the right hand magnet. Consequently, the rotation in a clockwise direction goes on until the contact 49 is carried over into engagement with the right hand contact 50. Then the right hand magnet winding is again short-circuited and the left hand magnet 87 again tilts member 80 to the position shown in Fig. 7; throwing the armature circuits back to the same condition they were first in. The electro-magnetic action of course immediately becomes that of positive retarding of the further movement in a clockwise direction, but the rotating system goes on through a movement to the right just as it did before to the left, until it is finally stopped and started back in counter-clockwise rotation. This operation of oscillation keeps up as long as switch S is closed. As soon as switch S is opened, then the oscillating system goes back to its normal gravity position, which is indicated in full lines in Fig. 9. Fig. 9 shows in dotted lines the typical upper terminal position of the signal member while it is oscillating. The whole system is balanced so that it has a slight tendency to come back to the position shown in full lines, normally standing in that position of rest. As soon, however, as the switch S is closed, the oscillating system, including the signal member A, immediately inverts itself, in a manner hereinbefore explained, and oscillation takes place, generally speaking, in this inverted position. The amplitude of oscillation of course may be varied by varying the position of stationary contacts 50; and the amount of over travel of the oscillating system, after having passed a contact 50, depends upon the inertia of the system and upon the strength of action of the electro-magnetic motor. In an actual mechanical embodiment of this device, with the contacts 50 set in the position shown in the drawings, the actual oscillation of the signal member is about 180° , or perhaps a little more. The amount of over travel may depend upon the current strength; and the adjustability of the contacts 50 allows a given oscillation arc to be kept, even though the current may vary somewhat. The oscillation is comparatively slow; approximately a movement from side to side in about two

seconds. This fact, connected with the fact that the oscillation is of very large amplitude, makes the signal extremely distinctive. And the fact that the signal may oscillate in a position which is distinctively different from its normal standing position also makes the signal an attention compelling one.

The whole switch mechanism 17 is adjustable upon shaft 13; the bushing 45 being set upon shaft 13 by means of a set screw 75 shown at 120. By reversing the position of the switch mechanism upon the shaft—by placing contact 49 in a normal position above the shaft—it will be seen that the signal mechanism would then oscillate through an 80 amplitude controlled by the position of contacts 50, but without inverting itself from its normal position. That is, if contact 49 normally stood above shaft 13, it will be seen that, as soon as the device started to rotate 85 in a counter clockwise direction, contact 49 would soon come into contact with left hand contact 50 and the direction of rotation would be reversed before the oscillating system had rotated very far. In the position 90 shown for contacts 50, the oscillation will be about 180° ; but by putting the contacts down as far as they will go, the oscillation may be increased to considerably more than a complete revolution. The circuit operations 95 and the operation of the reversing switch would be in this case exactly as before explained; the only difference in action is that the oscillating system does not invert itself before starting to oscillate. And it 100 will readily be seen, that by placing the switch mechanism in any intermediate normal position, the oscillating system may be made to oscillate in any desired intermediate position or zone, relative to its normal position. For instance, if the switch mechanism were set in a position ninety degrees from the normal position shown in the drawings, then, instead of the oscillating system inverting itself to oscillate, it would merely 110 move to and oscillate in a position where its center of oscillation was horizontal instead of vertical; and by putting the adjustable switch mechanism in a normal position at one side of the shaft, the signal member 115 would then oscillate through an amplitude controlled by the position of contacts 50, but without inverting itself from its normal position. That is, if contact 49 normally stood above shaft 13, it will be seen that, as soon as the device started to rotate in a counter-clockwise direction, contact 49 would soon come into contact with lefthand contact 50 and the direction of rotation would be reversed before the oscillating system had rotated very far. The circuit operations and the operation of the reversing switch would be in this case exactly as before explained; the only difference in action is that the oscillating system does not invert itself before 120 130

starting to oscillate. And it will readily be seen, that by placing the switch mechanism in any intermediate normal position, the oscillating system may be made to oscillate 5 in any desired intermediate position or zone, relative to its normal position. For instance, if the switch mechanism were set in a position ninety degrees from the normal position shown in the drawings, then, instead of the 10 oscillating system inverting itself to oscillate, it would merely move to and oscillate in a position where its center of oscillation was horizontal instead of vertical; and by putting the adjustable switch mechanism in 15 a normal position at one side of the shaft, the signal member may be made to oscillate with its arrow pointing in one direction; while by placing the switch mechanism in a normal position at the other side of the shaft, 20 the oscillating system and the signal member may be made to oscillate with its arrow generally pointed in the opposite direction.

All of these adjustments of amplitude and 25 position of oscillation are made possible by the features of balance and steady motor pull, as hereinbefore mentioned. It will also be understood that the fact of the motor being series wound makes for steady and heavy pulling qualities at low speed. But 30 the wiring arrangement is such that, even with the motor series wound, the total voltage is never at any time broken in the mechanism—the operations take place by shunting the current rather than by breaking it. 35 The circuit is always closed through one connection or another; and the interaction between the various shunt circuits practically eliminates all sparking at the switches.

It will be seen that bell coil 101 is in series 40 with the two magnet windings 86 and 87, in such a way that it would be continuously energized if it were not for the connection 109. Whenever the contact 83^a engages contact 85^a the bell is short circuited—the current for the coils 86 and 87 then passing 45 through wires 90 and 98, the switch contacts, and connection 109 rather than through wire 100, bell coil 101, and wires 103 and 105. This action gives intermittent 50 ringing of the bell without the necessity of entirely breaking the circuit. In fact, the circuit is never broken in the mechanism at all; all the actions are accomplished by diversion of current rather than by making 55 and breaking circuits. The non-inductive high resistance at 110 in parallel with the bell coil prevents arcing at the contacts 83^a, 85^a when they break contact.

While I have described my machine in detail 60 and specifically I have given this particular and full description of a preferred form for the purpose of rendering my invention fully intelligible in its broad as well as specific features, and not at all for the

purpose of limiting my invention to the specific mechanisms here set forth. Rather do I conceive this invention to be broad in its scope and not limited except as appears in the following claims which are to be interpreted broadly to the invention as well as 70 specifically to the particular embodiment of it here described.

Having described a preferred form of my invention, I claim:

1. In a device of the character described, 75 an oscillatable system balanced in substantially neutral equilibrium and including a signal member, means mounting said system for oscillation, and electro-magnetic means for oscillating said system including a rotary 80 motor having an inner field of small diameter and an armature of large diameter mounted for oscillation around said field, said armature forming a part of said oscillatable system. 85

2. In a device of the character described, 90 an oscillatable system balanced in substantially neutral equilibrium and including a signal member, means mounting said system for oscillation, and electro-magnetic means 95 for oscillating said system including a rotary motor having an inner field of small diameter and an armature of large diameter mounted for oscillation around said field, said armature forming a part of said oscillatable system and connected directly to said signal, the field being stationary and of the multipolar type and the armature having a multiplicity of coils. 100

3. In an oscillatable signal, an oscillatable system including means giving said system relatively great rotary inertia and balanced in substantially neutral gravitational equilibrium, means mounting said system to oscillate in a vertical plane, and 105 electro-magnetic means to cause oscillation of the system, said means including means to cause reversal of oscillatory movement by force applied solely by electro-magnetic means. 110

4. In a device of the character described, 115 an oscillating system, means pivoting said system to swing in a vertical plane and balanced in substantially neutral gravitational equilibrium but having a normal position of rest under gravity, an actuating electro-magnetic motor with a rotatable armature forming part of the oscillating system, and switch mechanism and circuits controlling the motor to cause it first to move the system from its normal position of rest to a different position and then to oscillate the system about its second mentioned position 120 as a center of oscillation. 125

In witness that I claim the foregoing I have hereunto subscribed my name this 14th day of November, 1919.

ROBERT R. THOMPSON.
